UNITED STATES PATENT OFFICE.

FRANKLIN ANDERSON RIDOUT, OF CYNTHIANA, KENTUCKY, ASSIGNOR OF ONE-HALF TO MARY M. ANDERSON, OF SAME PLACE.

REIN-HOLDER.

SPECIFICATION forming part of Letters Patent No. 644,461, dated February 27, 1900.

Application filed July 17, 1899. Serial No. 724,087. (No model.)

To all whom it may concern:

Be it known that I, FRANKLIN ANDERSON RIDOUT, of Cynthiana, in the county of Harrison and State of Kentucky, have invented 5 a new and Improved Rein-Holder, of which the following is a full, clear, and exact description.

The object of the invention is to provide a new and improved rein-holder which is simple and durable in construction, readily applied to the dashboard or other part of a vehicle, and conveniently and easily manipulated to receive and securely hold the reins and to allow of a quick removal of the reins 15 therefrom whenever desired.

The invention consists of novel features and parts and combinations of the same, as will be fully described hereinafter and then pointed out in the claims.

20 A practical embodiment of my invention is represented in the accompanying drawings, forming a part of this specification, in which similar characters of reference indicate corresponding parts in all the figures.

25 Figure 1 is a face view of the improvement as applied and with the reins held loosely in position preparatory to being clamped. Fig. 2 is a sectional side elevation of the same on the line 2 2 in Fig. 1, and Fig. 3 is a rear 30 face view of the same with the reins securely clamped in place.

The improved rein-holder is provided with a casing A, adapted to be fastened to the dashboard B, the whip-socket, or other part 35 of the vehicle, so as to bring the rein-holder within convenient reach of the driver. In the casing A are mounted to slide vertically clamping members C C', pivoted at their lower ends at C² and connected with each other to 40 engage at their outer upper ends the reins to be clamped in place, said members being arranged to be normally locked in an open position, as shown in Figs. 1 and 2, by a locking device consisting, essentially, of a latch 45 D, having a handle D' and pivoted on the member C and having a rounded edge D² at the free end to readily engage a pin D³ on the other clamping member C', the rounded edge terminating in a square shoulder D⁴, so as to 50 lock the clamping members C C' in an open position at the time the latch D is in a hori-

zontal position, the pin D³ abutting against the shoulder D⁴. (See Fig. 1.) When the latch D is in this position, it extends across the opening between the clamping members, 55 so that the reins passed between the upper ends of the clamping members rest with their lower edges on the latch D, and when a pressure is now exerted in a downward direction on said reins then the latch is swung downward to move the holder D⁴ out of engagement with the pin D³ and allow the upper ends 60 of the clamping members to close and clamp the reins in place. The shanks C³ and C⁴ of the clamping members cross each other at the 65 entrance of the shank at the upper end of the casing A at the opening A', the outer edges of said crossed shanks being beveled and in contact with the end walls of the opening A', so that when the members slide downward 70 when unlocked by the latch D then the clamping members are swung toward each other to securely clamp the reins between them. The downward - sliding motion of the clamping members C C' is accomplished by a spring E, 75 coiled around the lower ends of said members above the pivot C², the upper end of the spring E resting against bars F, secured to the casing, the lower end of said spring resting on a pin F', secured in one of the clamping members below the pivot C², as indicated in Fig. 3. 80

The extreme lower end C⁵ of the clamping member C passes through an opening A² in the bottom of the casing A to guide the lower pivoted ends of the clamping members in the 85 casing.

Now when the clamping members are locked in an open position, as shown in Figs. 1 and 2, and the reins are inserted between the clamping members and pressed downward to 90 cause the latch D to swing downward for unlocking the clamping members, then the spring E draws the clamping members downward and causes the upper ends thereof to swing toward each other by the shanks sliding with their beveled outer edges on the walls of the opening A'. Thus the upper ends of the clamping members securely clamp the reins between them. 95

When it is desired to release the reins from 100 the clamping members, the operator takes hold of the handle D' and swings the latch D

upward and in doing so causes the clamping members to slide upward in the casing against the tension of the spring E, and at the same time the rounded edge D² of the latch D by 5 coming in contact with the pin D³ swings the clamping members apart until the latch has assumed a horizontal position, the pin D³ resting against the square shoulder D⁴ to lock the members in an open position. The reins can 10 now be readily lifted out of the opened ends of the clamping members and the device is again in position for receiving the reins for again locking the same in position in the manner above described.

15 Having thus fully described my invention, I claim as new and desire to secure by Letters Patent—

1. A rein-holder, provided with clamping members pivoted together for clamping the 20 reins between them, and a locking device for locking the clamping members in an open position for the insertion of the reins, the locking device being arranged on the clamping members between their connecting-pivot and 25 their free ends, and being thus adapted to be actuated by the operator pressing the reins against it to unlock the clamping members for the latter to close, and to then automatically clamp the reins, substantially as shown and 30 described.

2. A rein-holder, provided with a casing, clamping members mounted to slide therein for clamping the reins between them, a locking device for locking the clamping members 35 in an open position for the insertion of the reins, the locking device being adapted to be actuated by the operator pressing the reins against it to unlock the clamping members for the latter to close, and to then automatically clamp the reins, and a spring connected 40 with the said clamping members, for imparting a sliding motion thereto relatively to the casing in one direction for closing the members, as set forth.

3. A rein-holder, provided with a casing, 45 clamping members for the reins, pivoted together and mounted to slide in the casing, and adapted to be closed thereby, a locking device for locking the members in an open position, and a spring pressing the said clamping members for sliding the same in one direction in the casing to close the members for clamping the reins, substantially as shown and described.

4. A rein-holder, provided with clamping 55 members pivoted together and mounted to slide into an open or closed position, a spring pressing the said pivoted members, and a latch pivoted on one of the clamping members and adapted to engage with its free end a pin on 60 the other clamping member, substantially as shown and described.

5. A rein-holder, comprising a casing or support, and pivoted clamping members engaging said casing and slidably longitudinally 65 to swing the clamping members on their pivot owing to their engagement with the casing.

6. A rein-holder, comprising a casing or support, pivoted clamping members engaging said casing and slidably longitudinally, and 70 a spring for moving the clamping members longitudinally to swing them on their pivot.

7. A rein-holder, comprising a casing or support, pivoted clamping members, and a latch pivoted to one member and extending 75 to a locking engagement with the other member across the space adapted to receive the reins, so that the latch is adapted to be engaged and operated by the reins.

8. The combination of the casing, the pivotally-connected clamping members slidable therein, the latch connecting the rein-holding portions of said members, and the spring for sliding the clamping members.

FRANKLIN ANDERSON RIDOUT.
